UNITED STATES PATENT OFFICE.

IRA SWARTZ, OF COALINGA, CALIFORNIA.

WELL-BAILING DEVICE.

1,253,106.

Specification of Letters Patent.

Patented Jan. 8, 1918.

Application filed June 29, 1917. Serial No. 177,783.

To all whom it may concern:

Be it known that I, IRA SWARTZ, a citizen of the United States, residing at Coalinga, in the county of Fresno and State of California, have invented certain new and useful Improvements in Well-Bailing Devices; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in bailing devices for emptying oil wells and consists of a simple and efficient device of this nature having various details of construction, combinations and arrangements of parts which will be hereinafter fully described, shown in the accompanying drawings and then specifically defined in the appended claim.

I illustrate my invention in the accompanying drawings, in which:

Figure 1 is a central vertical sectional view through the bailing device.

Fig. 2 is a cross sectional view on line 2—2 of Fig. 1.

Fig. 3 is a sectional view on line 3—3 of Fig. 1.

Reference now being had to the details of the drawings by letter, A designates the hollow cylindrical portion of the bailing device having open ends, and B is a shell fitted within said cylinder and provided with a central opening C, the marginal edge of the upper end of which forms a seat for a valve D. Said valve has a stem F projecting through the cylinder and has laterally inclined fingers H secured thereto, which are fastened at their lower ends to the circumference of a cylindrical-shaped, telescoping shell I, having the flexible bottom

K. Said shell I has shoulders N adapted to contact with the lower end of the cylinder when raised to limit its upper movement. A coiled spring O is interposed between said shells I and B and tends to normally hold the valve seated.

By the provision of a device embodying the features of my invention, it will be noted that a simple and efficient means is afforded whereby wells may be bailed, the cylinder being adapted to be passed down into the well with the bailer empty and which, when it reaches the bottom of the well, will cause a longitudinal movement to be imparted to the shell carrying the valve, thus unseating the latter and allowing the oil to enter. As the oil enters the cylinder, the lower part which is expansible becomes distended to carry the supply of oil as the device is hoisted.

What I claim to be new is:—

A bailing device for wells, etc., comprising a tubular shell having a circumferential shoulder, tubes fitted over said shell and abutting against said shoulder, one of said tubes having an interiorly beveled shoulder terminating at the adjacent end of said shell, a hollow cylindrical shell movable within one of said tubes, a stem having a split end forming fingers secured to said cylindrical shell, a ball valve with an aperture therein the wall of which is interiorly threaded to receive the threaded end of said stem, a flexible member fastened to the bottom of the movable cylindrical shell and provided with laterally extending openings and a central solid portion.

In testimony whereof I hereunto affix my signature in presence of two witnesses.

IRA SWARTZ.
